UNITED STATES PATENT OFFICE.

ANTON J. GAYDESKI, OF ENUMCLAW, WASHINGTON.

LOGGING DEVICE.

1,177,856.

Specification of Letters Patent.

Patented Apr. 4, 1916.

Application filed June 13, 1913. Serial No. 773,562.

To all whom it may concern:

Be it known that I, ANTON J. GAYDESKI, a citizen of the United States, residing at Enumclaw, in the county of King and State 5 of Washington, have invented certain new and useful Improvements in Logging Devices; and I do hereby declare the following to be a full, clear, and exact description of the invention, such as will enable others 10 skilled in the art to which it appertains to make and use the same.

This invention relates to new and useful improvements in logging devices and has for its object to provide a device for hauling 15 logs and automatically dumping the same.

Another object of my invention is the provision of a device which will eliminate the usual hand operated releasing mechanism.

Heretofore in clearing up stump land it 20 has been the practice for the men working thereon to erect what they term as a jimpole, which extends into the air for some fifty or sixty feet, the upper end of the jimpole having a sheave mounted therein and a 25 line passing over the sheave and one end is secured to the drum of a hoisting engine, while the opposite end is provided with a means for attaching a log. The logs and stumps to be destroyed are attached to the 30 line at the end opposite the hoisting engine and it will be seen that when the engine is started the rope will wind on the drum and cause the log to be dragged toward the jimpole and the logs and stumps in that 35 way will be brought to a pile which may then be burned or otherwise destroyed.

My invention has for its object the provision of an improved device for releasing the log from its position when it has reached

40 the proper point with relation to the log pile and with these and other objects in view I now proceed to describe my invention in the following specification and accompanying drawings, in which;

45 Figure 1 is a perspective view of an end of a log showing my improved attachment applied thereto, Fig. 2 is a diagrammatic plan view showing the layout used. Fig. 3 is a detail view of one of the locking hooks, 50 and Fig. 4 is a detail view of the jimpole.

Referring to the drawings by characters of reference 1 indicates a platform on which the usual stationary engine, indicated by the numeral 2, is mounted. The two separately rotated drums 3 and 4 are mounted on the 55 platform 1 and adapted to be operated by the engine. This engine and drums are preferably positioned at one side of the land which is being cleared at a point where it will be out of the way and will still be 60 close enough to effectively operate in connection with the remainder of the mechanism.

A suitable pole 5 is located in the center of the field and carries at its upper end a 65 sheave 6 which is rotatably mounted on a pivot 7, as clearly illustrated in Fig. 4. Arranged, as clearly illustrated in Fig. 2, I provide the blocks 7 and 8 which are secured in their position at the corners of the 70 field and around which the haul back line, which will be more fully hereinafter described, is adapted to extend.

The main line indicated by the numeral 9 is adapted to be wound upon the drum 4 75 mounted on the platform of the engine and is carried upward and over the sheave at the upper extremity of the jimpole and terminates at its opposite extremity in a loop 10, through which is passed a clevis 11. Pivotally secured between the arms of the clevis I provide the body portion 12 which terminates at its opposite extremity in a ring 13. A link 14 passes through the ring and connects the hook 15 therewith as is clearly 85 illustrated in Fig. 1. This hook 15 is provided intermediate its ends with an aperture 16, the use of which will be more fully hereinafter described.

The haul back line 17 is wound upon the 90 drums 3 and its opposite terminal extended, as clearly illustrated, and passes through the sheaves 8 and 7, as clearly seen in Fig. 2. The terminal of the haul back line opposite the drum is preferably secured to the link 95 18, which in turn is pivotally secured to a connecting member 19, the end of which opposite the link 18 is held between the arms of the clevis 20, by means of a suitable pivot pin 21. This clevis 20 is in turn passed 100

through the opening in the link 22 which is held in the aperture 16 formed in the hook 15.

A locking hook 23, which will be more fully hereinafter described, is adapted to be secured to one of the arms of the clevis as clearly illustrated and carries at its opposite extremity an eye 24, through which the end of the trip line 25 is adapted to pass.

10 The end of the trip line opposite the eye 24 is preferably looped, as clearly illustrated at 26, and co-operates with a ring 27 whereby the said end is secured to a hook 28, as clearly shown in Fig. 2.

15 A choker line 29 is provided which is adapted to be passed around the end of the log and one end secured to a clevis 30, which in turn extends through an aperture in the flat hook 31, this flat hook being preferably 20 cast, in the form illustrated, and provided at the side opposite the clevis 30 with an ear 32, having an aperture therein through which the link 33 is adapted to pass, this link 33 being substantially oval in contour 25 and adapted to receive the end of the hook 28, as clearly shown in Fig. 1. The end of the choker line opposite the clevis 30 terminates in a loop 34, which is adapted to be hooked over the hook 15, and it 30 will be obvious that when pull is exerted on the main line the choker line will be caused to clamp the end of the log and thereby hold the same.

The locking hook, previously mentioned, 35 preferably comprises a hooked member 35, terminating at one extremity in a loop 36, as clearly shown in Fig. 3. An aperture 37 is provided intermediate the hooked member 35 and the loop 36 and has a 40 transverse groove 38 communicating therewith. A locking pin 39 is slidably mounted in the aperture 37 and has formed integral therewith a depending portion 40 which is of the same shape as the slot 38 45 and when it is desired to slide the pin the member 40 is brought into alignment with the groove 38 and it will be obvious that the pin may be moved from its position in the hook.

50 In operation the line 9 is unrolled from the drum 4 and the end carried to the desired position. The choker line is then passed around the log, as shown in Fig. 2, and the loop 34 hooked on the hook 15. 55 Thus it will be seen that when pull is exerted on the main line the choker line will be tightened on the log and continued pull will cause the log to be dragged to the desired point. When it is desired to release 60 said log the drum 3 is caused to rotate, which will wind the haul back line and it will be seen that the hook 15 will be pulled rearwardly which will cause the loop 34 to slip off of the same and continued pull will 65 cause the trip line to pull the flat hook 31

from beneath the choker line and thereby release the log, without in any way necessitating the use of manual labor in connection with the releasing thereof.

While in the foregoing I have shown and 70 described the preferred embodiment of my invention, I wish it to be understood that I may change the specific arrangements of parts without in any way departing from the spirit and scope of my invention. 75

What is claimed is:—

1. A logging device including a choker line having a loop at one end and provided at the other end with a hook detachably engaging the choker line at a point intermediate of the ends thereof to form a sling for embracing a log, a main line having a relatively large hook provided with a bill disposed longitudinally of the main line and extending through the loop of the 85 choker line, a haul back line passing between the sling portion of the choker line and the log so as to be clamped against the latter and provided with means for connecting it with the relatively large hook at 90 the juncture of the bill and the shank thereof whereby the main hook will be maintained in a relatively rigid position when there is a strain on either the main line or the haul back line to maintain the loop positively on the said projecting bill while a log is being hauled and to enable the haul back line to positively withdraw the bill from the loop, said haul back line being also adapted to loosen the sling portion of the choker line 100 around the log and a trip line connected with the haul back line and with the hook of the choker line. 95

2. A logging device including a choker line having a loop at one end and provided at the other end with a hook detachably engaging the choker line at a point intermediate of the ends thereof to form a sling for embracing a log, said hook being provided at the juncture of the bill and the shank 110 with an eye, a link engaging the said eye, a main line having a relatively large hook provided with a bill disposed longitudinally of the main line and extending through the loop of the choker line, said relatively large 115 hook being provided at the juncture of its shank and the bill with an opening, a link engaging the said opening, a haul back line passing between the sling portion of the choker line and the log and provided with 120 means for connecting it with the link of the relatively large hook, said means including a clevis and the relatively large hook being maintained in a relatively rigid position 125 with relation to the main and haul back line when there is a strain on either of the said lines whereby the loop of the choker line is maintained on the bill while a log is being hauled and the bill positively withdrawn from the loop of the choker line 130.

when the haul back line is operated, said haul back line being also adapted to loosen the sling portion of the choker line from around the logs and a trip line provided at 5 its ends with hooks linked into the said clevis and into the link of the hook of the choker line.

In testimony whereof I affix my signature in presence of two witnesses.

ANTON J. GAYDESKI,
